MERCURY INTERRUPTER

William S. Brian, Owensboro, Ky., assignor to
 General Motors Corporation, Detroit, Mich., a
 corporation of Delaware

Application March 17, 1939, Serial No. 262,396

2 Claims. (Cl. 200—113)

This invention relates to circuit controlling means and more specifically to automatic circuit interrupters. It has subject-matter in common with the same type of interrupter as disclosed in my copending applications Serial No. 241,383 filed November 19, 1938, and Serial No. 241,384 filed November 19, 1938, and deals specifically with improvements thereover.

With the type earlier disclosed it has been difficult to obtain operating frequencies slow enough for various types of apparatus, for example, fuel pumps. It has also been found that the carbon tip wears away to some extent. It is the object of the present disclosure to provide an interrupter which operates at a comparatively low frequency and also one in which the life of the carbon tip is substantially lengthened.

The embodiments of my invention will therefore be better understood by reference to the following specification and claims and illustrations in the accompanying drawing, in which:

Figure 1 is a vertical section through an interrupter of my invention;

Figure 2 is a similar view of a portion of the interrupter showing a different stage in the operation thereof; and

Figure 3 is a vertical section through a portion of a modified form of interrupter similar to Figure 2.

The present type of interrupter is shown as comprising a main outer envelope 2 which in the present instance is shown as glass but may consist of any type of suitable housing, at least a portion of which is of electrically insulating material so that the two electrodes are electrically isolated. The general form of the envelope 2 is tubular and one end of the member is heated and pressed around an electrode 4 to support the same, said electrode 4 projecting into a center chamber 6 a substantial amount. The lower end of the envelope 2 is also pressed around an electrode assembly composed of a metal wire 8 which is staked into a small carbon mass 10 and the glass drawn tightly around the two to support the assembly in the lower end of the envelope.

The upper end of the carbon mass 10 comprises a small projecting tip 12 which projects through a glass partition and extends a short distance into the center chamber, the outer envelope being drawn in to form a restricted area 14 adjacent this tip. A pool of mercury 16 is enclosed within the envelope and the device normally operated in the position shown, the mercury flowing down through the restriction 14 and resting upon the end of the electrode 12, a portion of the space

surrounding the electrode 12 being filled only with mercury vapor since the surface tension of the mercury prevents it from flowing in to all the crevices as shown in Figure 1.

As current is applied to the two electrodes 4 and 8 and flows through the mercury bath, the mercury actually in contact with the carbon tip 12 is heated to such an extent that it is vaporized and this vapor forces the body of mercury upwardly to such a position as shown in Figure 2. This of course causes the circuit between the electrodes to be broken and the weight of mercury causes the mercury to again descend, compressing and condensing the mercury vapor until it again contacts the tip 12 and the cycle is completed. The operation of this device may be described as autonomic in that it is self-governing and requires no separate or outside control.

Thus, as in former cases, we have an automatic, periodic circuit interrupter, but in this instance the restricted neck 14 prevents the mercury from again coming in contact with the carbon tip 12 as soon as it would if the restriction were not present and in this manner slows down the normal operation of the device so that it has been possible to operate tubes of this design at frequencies of from 5 to 30 cycles per second, for example, and to pass fairly high power currents therewith. By designing the area of this neck therefore we are able to control to some extent the speed of operation. This geyser effect also causes a more rapid quenching of the arc.

Since the carbon tips in these devices have worn and where they were provided flush with the glass surface have cratered after long wear to such an extent that the mercury does not flow deep enough to cause proper contact, it has been found that in this type of device it is satisfactory to allow the carbon tip to project a certain amount above the surface of the glass. As previously explained, the surface tension of the mercury prevents the same from flowing down around the sides of the tip so that actually there is no more carbon surface in contact with the mercury than if the same had been ground off flush with the glass and therefore I am able to obtain a decided increase in life of the carbon point and in no way affect the other characteristics of the interrupter.

It has also been found that the carbon point may be coated with a very thin layer of suitable metal for the same purpose; namely, that of increasing the life. The metal used must have a high melting point and resist amalgam with mercury. I have found through experimentation that

by coating the end of the carbon button with a layer of molybdenum, such as at 22, that the surface will last considerably longer and also that I may control to some extent the characteristics 5 of the interrupter. By this is meant that during one complete cycle various interrupters have differing off and on times and with this metal coating I have found that the on time for the cycle can be increased. In this manner the cyclic 10 characteristics of the interrupter may be predetermined and definitely designed and manufactured. This metal surface may be deposited by electrodeposition or a small metal clip may be mechanically pressed on the carbon tip when it 15 is made, either manner operating satisfactorily.

In Figure 3 is shown a modified form of my invention in which instead of having the area directly above the carbon tip 12 tapered, since the mercury does not flow around the sides of the 20 carbon, the same may be straight and merely a cylindrical-necked portion such as 20 may be provided above the carbon tip 12 to give substantially the same results.

I claim:

25 1. In an autonomic interrupter, an envelope, two spaced contacts carried thereby, a body of mercury adapted to bridge the contacts carried by the envelope, one of the contacts being of

higher resistance than mercury and of such area as to cause high current density therein whereby current passing through the juncture of the contact and the mercury causes vaporization of the latter and displacement and a restriction in the 5 envelope adjacent the contact to impede the flow of the mercury back to its initial position and thus slow up the cyclic operation of the interrupter.

2. In an autonomic interrupter, an envelope 10 providing a chamber, a pair of spaced electrodes extending into said chamber, one of said electrodes being formed of carbon and projecting a short distance into the chamber and having a definite surface area to provide high current density 15 at given operating currents, a restriction in the envelope adjacent the carbon electrode providing a relatively small chamber, a body of mercury sufficient to bridge the two electrodes whereby when current flows through the mercury and 20 the two electrodes and the heat generated by the carbon electrode vaporizes some of the mercury in the small chamber, the mercury will be forced away from the carbon electrode and out of said small chamber and slowly flow back upon condensation of the mercury vapor to again complete the circuit. 25
